UNITED STATES PATENT OFFICE

LLEWELLYN N. HALEY, OF CLEARWATER, FLORIDA; GRACE L. HALEY, EXECUTRIX
OF SAID LLEWELLYN N. HALEY, DECEASED

RUG FRAME

Application filed December 8, 1928. Serial No. 324,751.

This invention relates to store furniture and more particularly to a novel device for displaying rugs to prospective purchasers.

One of the primary objects of the invention is to provide an attachment for rug displaying racks, the attachment embodying novel means for permitting the raising of a rug from a pile of rugs on the rack to a displaying position.

10 Another salient object of the invention is to provide an attachment for rug displaying tables or racks embodying a swinging frame with novel means for raising the frame for moving a rug to a displaying position from a pile of rugs upon the rack or table.

A further object of the invention is the provision of a novel swinging rug displaying frame for connection with a rug display table or rack, with means for raising and lowering the frame, the frame being adapted to be lowered upon the pile of rugs, so that the desired rug to be displayed can be folded over the end of the rack with means for holding the adjacent rug against movement, whereby upon the raising of the frame, the desired rug will be conveniently and expeditiously removed from the pile of rugs without disturbing the other rugs upon the table and rack.

30 A still further object of the invention is to provide means for removing and displaying a rug from a pile of rugs of the above character, which will be durable and efficient in use, one that will be simple and easy to manufacture, and one which can be placed upon the market and incorporated with a conventional rug displaying table or rack at a small cost.

With these and other objects in view, the invention consists in the novel construction, arrangement and formation of parts, as will be hereinafter more specifically described, claimed, and illustrated in the accompanying drawing, in which drawing:

45 Figure 1 is a rear elevation of the improved rug displaying device.

Figure 2 is a side elevation of the same.

Figure 3 is a detail section taken on the line 3-3 of Figure 1 looking in the direction of the arrows, illustrating the support-

ing bearings for the swinging display frame.

Figure 4 is a similar section taken on the line 4-4 of Figure 1 looking in the direction of the arrows, illustrating the means for connecting the swinging frame with the supporting and operating shaft. 55

Figure 5 is a detail section taken on the line 5-5 of Figure 4, and

Figure 6 is a detail section taken on the line 6-6 of Figure 5 looking in the direction of the arrows. 60

Referring to the drawings in detail, wherein similar reference characters designate corresponding parts throughout the several views, the letter A generally indicates a conventional table or rack upon which a pile of rugs B can be placed and C my improved mechanism for moving one of the rugs to a displaying position from the pile. 65

As stated, the rug displaying table or rack A can be of any conventional or preferred character and is of the usual low construction embodying the top 10, the side pieces 11, and the short supporting legs 12. In accordance with the usual practice, the rugs B are placed in a pile upon the table A and considerable difficulty has been experienced when it is desired to remove an intermediate rug from the pile. In the past removing rugs from the rack has been a very slow operation taking so two men to remove and place rugs back in position about twenty minutes. My improved attachment C will permit one man to remove any desired rug in about three minutes. 70 75

As shown the attachment C comprises a transversely extending rock shaft 15 rotatably mounted in suitable bearings 16 which can be secured at spaced points to one rear piece 11. Each bearing 16 includes a lower body block 17 and a top cap 18 between which the rock shaft 15 is received. 80

This rock shaft 15 supports the lifting or display frame 20 which can be constructed from any desired material. In the present instance I have shown the frame 20 constructed from a plurality of spaced parallel longitudinally extending T-shaped bars 21 connected by transverse straps 22 forming a substantial rectangular open frame. 85

This frame 20 is connected to the shaft by 100

the use of suitable clamps 23 which includes upper and lower blocks 24 and 25 connected together by suitable bolts 26. The lower block 25 can receive the inner ends of the longitudinally extending bars 21 and the blocks can be provided with suitable guideways for receiving the T-bars so that the frame can be adjusted on the shaft if preferred. The shaft 15 is securely clamped between the two blocks 24 and 25 and it is obvious that upon rotation of the shaft that the frame 20 will be moved toward and away from the pile of rugs.

At one side of the table A, I can arrange a substantially U-shaped supporting standard 30, which can be rigidly secured to the floor adjacent to the table or can be directly secured to the table if preferred. The shaft 15 extends through suitable bearings in the arms of the standard and has keyed or otherwise secured thereto a pinion 31 which meshes with a drive gear 32 keyed or otherwise secured to the operating shaft 33. This operating shaft 33 is rotatably supported by the arms of the standard and has formed thereon or secured thereto a suitable crank 34 whereby the rock shaft 15 can be actuated to raise and lower the displaying frame 20.

In order to hold the frame 20 in elevated position I can provide the ratchet wheel 35 which can be keyed or otherwise secured to the operating shaft 33 and the ratchet wheel can be held against movement in one direction by the use of a suitable pivoted pawl 36.

In operation of the device, as so far described, when it is desired to move a rug to displaying position the displaying frame 20 is moved to a lowered position on the top of the pile of rugs and one end of the rug can be pulled outward from the pile and thrown over the free edge of the displaying frame 20 after which the displaying frame can be raised through suitable manipulation of the crank 34.

In case an intermediate rug in the pile is to be moved to a displaying position, which say is the tenth rug in the pile, the same can be pulled outward and then thrown over the free edge of the displaying frame 20, the ninth rug being clamped to the table against movement, after which the display frame is raised by the crank, which will quickly pull the rug from out of the pile of rugs to a displaying position.

Any desired means can be provided for clamping the intermediate rug against movement, while a rug is being pulled from the pile to a displaying position and this clamping means may include a pair of upright bars 37 and 38 anchored in the table top. Slidably mounted on each of the bars or rod 37 and 38 is a clamp 38' for gripping contact with the rug which is to be held against movement. The clamps can each include adjustable jaws and the clamps can be held in ad-

justed position on the rods by suitable thumb screws or the like.

From the foregoing description, it can be seen that I have provided a novel rug displaying device which will permit the quick and expeditious pulling of a rug from a pile of rugs without undue work on the part of the salesman.

Changes in details may be made without departing from the spirit or the scope of this invention, but what I claim as new is:

1. The combination with a rug displaying table for receiving a pile of rugs, of a displaying and lifting device comprising a rock shaft rotatably carried by one end of the table, a frame secured to the rock shaft for movement toward and away from the pile of rugs, for suspending a rug for display above the table when the frame is in a raised position, and means for rotating said shaft.

2. The combination with a rug displaying table for receiving a pile of rugs, of means for removing a rug from the pile to a displaying position including a rock shaft arranged at one end of the table, a frame secured to the rock shaft for movement toward and away from the table for receiving the rug to be displayed, means for rotating the rock shaft, and means for holding the rock shaft normally against movement in one direction.

3. The combination with a rug displaying table for receiving a plurality of superposed rugs, of an attachment for the table comprising a rock shaft, a frame carried by the rock shaft for movement toward and away from the face of the table for receiving a rug to be pulled from the pile and moved to a displaying position, a rotatable operating shaft, a gear on the operating shaft, a pinion on the rock shaft meshing with said gear, means for operating the operating shaft, and means for normally holding the operating shaft against movement in one direction.

4. The combination with a rug display table of an attachment therefor for removing a single rug from a pile of rugs placed upon the table comprising a frame of substantially the size and configuration of the table top, over which the rug to be displayed is adapted to be placed, whereby the rug to be displayed can be suspended in a substantially vertical plane above the table when the frame is in a raised position and mechanical means for swinging the frame toward and away from the table top.

5. The combination with a rug displaying table adapted to receive a pile of superposed rugs, of an attachment therefor for removing an intermediate rug from the pile including a swinging frame movable toward and away from the table top over which an intermediate rug in the pile can be folded, when the frame is in a lowered position, means for raising and lowering the frame,

and adjustable means whereby the top adjacent rug to the rug being removed will be held against movement.

6. The combination with a display table for receiving a pile of superposed rugs, of an attachment associated therewith for removing an intermediate rug from the pile to a displaying position comprising a frame hinged at one end of the table for movement 10 toward and away from the table top and of substantially the same size and configuration as the table top over which an intermediate rug in the pile can be folded, means for raising and lowering the frame relative to the table top, and a pair of jaw members adjustable relative to one another and to the table top for engaging the top adjacent rug to the rug being removed, whereby the intermediate rug can be pulled from the pile without disturbing the other rugs in said pile.

20 7. The combination with a display table for receiving a pile of superposed rugs, of an attachment associated therewith for removing an intermediate rug from the pile to a displaying position comprising a frame hinged at one end of the table for movement 25 toward and away from the table top and of substantially the same size and configuration as the table top over which an intermediate rug in the pile can be folded, means for raising and lowering the frame relative 30 to the table top, and a pair of jaw members adjustable relative to one another and to the table for engaging the top adjacent rug to 35 the rug being removed, whereby the intermediate rug can be pulled from the pile without disturbing the other rugs in said pile.

In testimony whereof I affix my signature.
LLEWELLYN N. HALEY.
